UNITED STATES PATENT OFFICE.

FREDERICK W. LINAKER AND THEODORE M. BRUBACK, OF DUBOIS, PENNSYLVANIA.

AIR-COOLED SOOT CLEANER.

Application filed October 18, 1921. Serial No. 508,604.

To all whom it may concern:

Be it known that we, FREDERICK W. LINAKER and THEODORE M. BRUBACK, the former a subject of the King of Great Britain, and the latter a citizen of the United States of America, both residing in Dubois, in the county of Clearfield and State of Pennsylvania, have invented certain new and useful Improvements in Air-Cooled Soot Cleaners, 10 of which the following is a specification.

This invention relates to devices for cleaning tubes or the interior parts of boilers, economizers and the like, commonly known as soot cleaners, and aims to provide improvements therein.

In those soot cleaners where the cleaner element is permanently mounted in a hot part of the furnace or boiler setting there is liability of the cleaner element being burned 20 out or injured by the heat during the periods of disuse when it is not cooled by the flow through it of a cleaning fluid (usually steam). To protect such cleaner element from injury by heat it has been proposed to surround the 25 element with a pipe or jacket and cause a cooling fluid to circulate through such jacket; in one instance water has been used as the cooling medium; in another instance it has been proposed to use air as such medium.

The present invention provides improved cooling means designed to successfully cool the element by means of air.

According to the present invention the soot 35 cleaner element is surrounded by a cooling jacket through which outer air is drawn by suction, the suction being due to a connection with the furnace draft so located that the air flowing through the jacket is not discharged 40 into the furnace where it will dilute the fire gases, but is introduced beyond where these gases act upon the boiler tubes, that is to say, beyond the final pass through the boiler structure so as to mingle with the spent gases 45 and be drawn away to the stack. Other features of improvement will be hereinafter set forth.

Several embodiments of the invention are illustrated in the accompanying drawings.

50 In said drawings,

Figure 1 is a longitudinal sectional view of a cleaner embodying the invention and shown applied to a single boiler, the view being taken from beneath as indicated by the 55 arrow I in Fig. 6.

Fig. 2 is a similar view of a second modification, showing the device applied to one boiler of a battery.

Fig. 3 is a cross section on the line 60 III—III, Fig. 2.

Fig. 4 is a section on the line IV—IV, Fig. 2.

Fig. 5 is a view in cross section illustrating a third embodiment of the invention.

Fig. 6 is a sectional side elevation of a 65 boiler of the Babcock & Wilcox type and its setting, showing the location of the cleaner element and piping.

In said drawings, numeral 1 designates a 70 cleaner tube or element, here shown as of the rotary type, provided with a sprocket wheel 2, and connected to a steam line 3 through a stuffing box or the like 4. Said tube or element 1 is provided with nozzles or orifices 5 through which jets of cleaning fluid, as for example steam, are projected upon designed parts of the interior of a boiler, and, as will be readily understood, the jets are directed 75 upon different parts of the boiler by rotating the tube or element by means of the sprocket 80 2. When such cleaner elements or tubes are located in hot parts of a boiler the metal is apt to become burnt, or to soften, causing the tube to bend, thereby very much shortening the life of such elements. Hence, especially where such cleaner tubes or elements 85 are located in very hot parts of the boiler setting, it is desirable to provide means for cooling said tube or element. Such cooling means conveniently comprise a tube or jacket 90 7, preferably concentric with the tube 1, with a space 8 between said tubes, for the flow of cool air drawn from outside the boiler. The tube or jacket 7 is conveniently held in spaced relation to, and affixed to, the tube or element 1, by suitable means, as for example, set screws 9. The tube or jacket 7 is in communication with the outside air, as through an opening 10 in the end of the tube or jacket 7, said tube or jacket 7 preferably being made to extend to the exterior of the 95 boiler.

The space 8 in the tube or jacket is also 100 in communication with a means for inducing a flow of cool air therethrough, such means being (most conveniently) the draft means of the boiler or furnace, said space 8 being connected to a suitable part of the boiler setting where the draft is active, as by means of a suitable tube or conduit 12. There is 105 110

preferably provided a box 13 in the boiler wall, with which the space 8 in the tube 7 communicates, and with which the conduit 12 also communicates. The box 13 also conveniently provides a bearing for an end of the pipes 1 and 7.

The draft of the furnace acting through the conduit 12 induces or creates a reduced pressure in the space 8 within the jacket 12, thus inducing or creating a flow of air through the opening 10, the space 8 within the jacket and the conduit 12 to the interior of the boiler setting, or to the breeching or smoke stack, or any suitable point beyond the active boiler surface. This result may be attained by carrying the end 12' of the conduit 12 through the furnace wall and into the boiler setting to the position shown at 12' in Fig. 6, which in the case of a boiler 20 of the Babcock & Wilcox type here shown or any analogous construction brings the outflow of air at 12' to the top of the third pass and beyond where the fire gases act upon the boiler tubes so that any cooling or dilution 25 of the fire gases by the influx of cooling air does not detract from the heating effect upon the boiler tubes.

The arrangement thus far described is that for a single boiler where access can be had to the furnace walls on both sides. Where boilers are arranged in a battery or with any arrangement where access can be had on only one side a different arrangement is required, since the outside air must enter 35 and the suction be taken off from the same end of the jacket on the same side of the boiler. In such case in addition to the box 13 located at the end of the element opposite the entering end of the cleaning fluid, a box 15 may be provided, as shown in Fig. 2. The tube or jacket 7 preferably extends through the box 15, said box 15 being in communication with the interior of said tube 7 through an opening 16. The conduit 12 (on which acts the draft of the furnace) is connected to the box 15. Packing glands 17 may be provided upon the box 15 around the tube or jacket 7. The tube or jacket 7 may be partitioned as shown in Figs. 2, 3 and 4, 45 to provide for a flow of cooling fluid lengthwise of the tube or jacket in one direction and a return flow in the other direction. The space within the tube or jacket 7 may be divided into two parts, as by means of bars 18-18 as shown in Fig. 3, providing two spaces 20-21 within the jacket 7. The space, as for example the space 20, at the end of the tube which communicates with the open air is preferably stopped or closed, 50 as indicated at 22, Fig. 4, an inlet for air being provided at the open end 23 of the other space 21 within the tube 7.

The draft of the furnace acting through the conduit 12, box 15 and opening 16 creates 55 a reduced pressure in the space 20 within the

jacket, which in turn reduces the pressure in the other space 21 (the spaces 20 and 21 being conveniently in communication through the box 13) and thereby induces or creates a flow of air through the inlet 23, 70 through the spaces 21 and 20 and thence to the interior of the boiler setting through the pipe 12.

Another form in which the jacket may be partitioned is illustrated in Fig. 5. As 75 shown in said figure the pipe 1 for conveying the cleaning fluid, except at its inlet end, is off-set, as indicated, and a pipe 25 is placed along with it in the tube or jacket 7. The tube 25 serves to conduct air from the inlet in front of box 15 to the opposite end of the tube, the return flow being 80 through the spaces 26, surrounding the two pipes 1 and 25 within the jacket 7.

It has heretofore been proposed to cool 85 a cleaner element by surrounding it by an outer pipe or jacket taking exterior air through a small tube within the cleaner element leading it thence into one end of such jacket and providing at the other end 90 of the jacket within the furnace chamber a series of perforations for the escape of air. With such construction the flow of air is 95 greatly restricted because the air inlet pipe must be small enough to avoid obstructing the flow of steam to the cleaner nozzles, so that because of such restriction the flow of air is inadequate; while the discharge of the cooling air through perforations at one end 100 of the cleaner element involves the cooling and dilution of the fire gases at that end, the cooling effect of which continues for a considerable distance on that side of the boiler, which not only diminishes the steaming capacity of the boiler but also produces 105 inequalities of temperature which occasion unequal strains in the boiler structure. All such defects are obviated by the present invention which enables air to be circulated to the full capacity of the jacket thereby 110 accomplishing a maximum cooling effect, and this is attained without dilution or cooling of such gases until after they have 115 passed beyond the active boiler surface; thus our invention avoids any diminution of the steaming rate and also avoids introducing any inequalities of temperature.

It has also been proposed to cool the 120 cleaner element by causing water to flow through the surrounding jacket. This requires forcing the water through under pressure, and it has been found impossible to prevent leakage of the water and other troubles due to the expansion when the elements are in service. Such water-cooled element is also liable to the formation of scale in the annular space within the jacket, which 125 defeats the operation of the cooling means.

The inventive ideas as herein set forth 130 may receive other embodiments than those

herein specifically illustrated and described.

What we claim is:

1. A soot cleaner element having an enclosing jacket open at one end to the outer air and a conduit leading from the other end and terminating in communication with a portion of the furnace where the fire gases have passed beyond the active heating surface of the boiler whereby the furnace draft induces a copious flow of air through said jacket to cool the element, and the air discharged from the jacket does not dilute or cool the combustion gases until after they have passed beyond the heating surfaces of the boiler.
2. An air cooled soot cleaner element having a jacket open to the atmosphere at one end and a conduit leading from the opposite end of such jacket to a point between the active heating surface of the boiler and the furnace stack where it is subjected to a

strong suction for drawing cooling air through such jacket, whereby the air discharged from the jacket does not dilute or cool the combustion gases until after they have passed beyond the heating surfaces of the boiler.

3. An air cooled soot cleaner element comprising a surrounding jacket open at one end to the atmosphere, a longitudinal partition within such jacket with a chamber at the opposite end connecting passages on opposite sides of such partition, the air inlet communicating with one such passage, and a conduit leading from the other passage at the inlet end and terminating in a draft connection beyond the active heating surface of the boiler.

In witness whereof, we have hereunto signed our names.

FREDERICK W. LINAKER.
THEODORE M. BRUBACK.
